(57) **CLAIM**

The ornamental design for a china cabinet, as shown and described.

DESCRIPTION

FIG. 1 is a left front perspective view of a china cabinet showing my new design;

FIG. 2 is a front elevational view thereof;

FIG. 3 is a side elevational view, the opposite side being a mirror image thereof; and,

FIG. 4 is a front perspective view thereof, with scene in dashed lines.

The dashed lines represent environmental elements only and form no part of the claimed design.
